UNITED STATES PATENT OFFICE.

JOHN A. MOORE, OF LOUISVILLE, KENTUCKY, ASSIGNOR TO THE MENGEL COMPANY,
OF LOUISVILLE, KENTUCKY, A CORPORATION OF NEW JERSEY.

MACHINE FOR NOTCHING BLANKS.

1,404,788.

Specification of Letters Patent. Patented Jan. 31, 1922.

Application filed July 9, 1919. Serial No. 309,557.

To all whom it may concern:

Be it known that I, JOHN A. MOORE, a citizen of the United States, residing at Louisville, in the county of Jefferson and 5 State of Kentucky, have invented certain new and useful Improvements in Machines for Notching Blanks, of which the following is a specification.

This invention pertains to an improved 10 machine for notching and cutting blanks employed in the making of packing cases or boxes. While the machine is adapted to the notching and cutting of stock of various thicknesses, it is especially adapted for 15 handling relatively heavy fiber board such as is now commonly employed in bent up or formed cases or boxes.

The invention has for its main object an 20 arrangement of the shearing blades or cutters so that they may act successively and preferably in oppositely disposed pairs, whereby the machine may be operated with a minimum of power and without undue strain upon the mechanism.

25 A further object is the provision of means whereby the machine is readily adapted to the handling of different sizes of blanks. A still further object is to provide means for feeding and arresting the stock in proper 30 position and relation to the shearing blades or cutters.

The invention has for its further object the provision of means whereby the cutters will be automatically brought into operation 35 when the blank is positioned and thereafter arrested while the finished blank is being fed outwardly and another blank brought to place.

With these and other objects in view, a detailed description of a preferred embodiment 40 of the invention will be given, reference being had to the annexed drawings, wherein:

Fig. 1 is a top plan view of the machine;

Fig. 2 a side elevation;

45 Fig. 3 a vertical longitudinal section on the line III—III of Fig. 1;

Fig. 4 a transverse vertical sectional view on the line IV—IV of Fig. 3;

Fig. 5 an end elevation of the machine 50 as viewed from the intake end;

Fig. 6 a similar view of the discharge end;

Figs. 7, 8 and 9, detail views of the clutch releasing and engaging means which is caused to function by the positioning of the 55 stock or blank;

Fig. 10 a detail view of one of the shear or cutter blades;

Fig. 11 a transverse section on the line XI—XI of Fig. 10;

Fig. 12 a detail view of the cutter employed to cut the stock or blank at one end thereof;

Fig. 13 a sectional view on the line XIII—XIII of Fig. 12;

Fig. 14 a detail sectional view on the line XIV—XIV of Fig. 10; and

Fig. 15 a perspective view of the notched and cut blank.

The frame of the machine may be said to comprise two trough shaped base or foot 70 pieces 1 and 2, and a pair of vertically disposed plate-like members mounted in each base and designated respectively by 3 and 4 and 5 and 6, the plates of the opposite pairs being connected by stay rods 7 and 8. The 75 plates 3 and 5, and 4 and 6, are likewise connected to each other by horizontally disposed beams 9 and 10, see more particularly Fig. 4, the plates being provided with inwardly 80 projecting portions 11 which the ends of the beams abut. The plates are preferably flanged so as to render them stiff and rigid.

To effect adjustment of the plates or frame members 3 and 4 and 5 and 6 toward and from each other, I provide a screw-threaded shaft 12 for each plate, the shafts 85 passing through nuts 13 secured to the plates, while the outer ends are journaled in bearings 14 secured to the base pieces 1 and 2. Sprocket chains 15 pass about sprockets 16 90 secured to shafts 12 and by turning one of said shafts, as by the application of a wrench thereto, the companion shaft will be likewise rotated and the frame elements 3 and 5 or 4 and 6, as the case may be, will be simultaneously moved in or out toward the center line of the machine. This adjustment is for the purpose of bringing the oppositely disposed series of shear or cutter blades closer together or spacing them further apart to 100 vary the depth of the cuts or slots made in the stock.

Secured upon the upper face of each of the end plates or frames is a bearing 17 and extending from the oppositely disposed pairs 105 of bearings and mounted therein are shafts 18 (two in number) said shafts lying parallel to each other and to the medial line of the machine. Said shafts carry the movable shear blades which are duplicated upon each 110

side of the machine and in part are similar on the same side of the machine; like blades and their allied and cooperating parts will therefore be designated by the same reference numerals.

The blank, designated generally by B, is in the instant case designed to be cut and notched as shown in Fig. 15, wherein there is formed in each side two similar cuts or notches 19 and 20, and an intermediate notch 21, the root whereof is cut at an angle the reverse of that of the others. The blank at the forward end is cut away adjacent each side, as at 22, and the opposite end has two somewhat wider pieces cut out, forming relative deep recesses 23, the reentrant angle whereof is a right angle. The cutters or blades which produce the notches 19, 20 and 21, and the cutaway sections or recesses 22 are alike in form except for the fact that the angle formed on the ends of the movable blades and the cooperating fixed blades or die plates is reversed for the production of 19 and 20 from those producing 21 and 22. The shear blades are designated by 24 and extend outwardly from a hub 25, see Fig. 14, which is mounted on shaft 18, the hub being longitudinally adjustable thereon and held in its adjusted position by a key 26 which takes in a key-way formed longitudinally of the shaft and also in the hub. A set screw 27 mounted in the hub and bearing at its inner end upon the key serves to lock the key in place. The hub is embraced between and journaled in two collar like members 28 which are formed as extensions of two horizontally disposed arms 29—29, which are connected at their inner ends by a cross piece 30 which rests upon the beam 9 (or 10) said cross piece having an underlying hooked shaped member 31, Fig. 10, which embraces the flange of the beam. Said hubs, arms and member 31 form a frame which is adjustable along the shaft 18 and the beam, and upon which frame is mounted and secured the fixed shearing blade or die, denoted by 32, see Figs. 1, 10 and 11. The blade 24 is beveled upon its under face and the end thereof is inclined, and the die plate is inclined at its end to conform to the bevel of the end of the blade 24. By reason of this arrangement a shearing action is effected and the stock is cut away clean and with a minimum expenditure of power at any one time. Moreover to the same end the various blades are offset about the shaft and come into action successively.

The cutter employed to produce the recesses 23 is constructed in the same general manner. Instead of forming the movable cutter as an extension of the hub, an arm 33, Figs. 2, 5 and 12, extends from the hub, and a block 34 is secured thereto. Said arm has secured to it oppositely disposed blades

35 which coact with fixed shear blades 36 secured upon the adjacent arms 29, said blades being connected at their inner ends by a cross blade of shearing element 37.

The blanks or sheets as they are fed to the machine are supposed to be cut to the proper length at the pasting of blank forming machine, but in setting up the pasting machine, until the operator gets the proper length of the sheet, he will get several sheets that are too long for the ordinary stitching lap 38 at the end of the blank, Fig. 15. By the employment of the double knife, a notch is cut out of the over-length blank, indicated in said figure, and when such blank comes to the stitchers the excess may be cut off with a knife of any sort to make the box of proper length, thereby saving all sheets which would otherwise be lost or have to be trimmed off before going through the regular notching process.

The shafts 18 rotate in unison and in opposite directions, each shaft having secured thereto a bevel gear 39 which mesh, respectively, with similar gears 40 splined on a cross shaft 41, Figs. 1, 3 and 5, mounted in bearing secured to the frame plates 3 and 4. Said shaft also carries two pulleys 42 and 43, about which pass feed belts 44 and 45, said belts extending lengthwise of the machine and about driving belt pulleys 46 and 47 secured to a shaft 48, see Figs. 1, 3 and 6. Said shaft finds its bearings in brackets 49 secured, respectively, to the frame plates 5 and 6. Motion is imparted thereto through a belt 50, and belt 51, fulcrumed on the shaft serve to keep the belts 44 and 45 taut. A second pair of feeding belts 52 and 53 underlie the belts 44, 45, said second pair at the forward or infeed end of the machine passing about idler pulleys 54 and 55, respectively, supported upon stub axles carried by the frame plates 3 and 4, Fig. 5. At the discharge end of the machine the belts pass about pulleys 56 and 57 mounted on a shaft 58 supported in the lower portions of brackets 49, said shaft being driven by a belt 59. Belt 50 being crossed, shafts 48 and 58 are driven in opposite directions, and, as a consequence, the adjacent or innermost run of each pair of the feeding belts 44, 45, and 52 and 53, travel in the same direction from the forward to the discharge end of the machine. The belts moreover are constantly driven and the stock is carried forward thereby and periodically brought to rest in position for the action of the shearing blades or knives. To sustain the blanks along their medial line as they pass through the machine a bar 60^a, Figs. 1, 3 and 5, supported by uprights 60^b, is placed intermediate the feed belts and extends lengthwise of the machine.

To prevent the blank from shifting later-

ally and to maintain it in proper operative relation with the knives, edge guides are provided which may take the form of flaring angular shaped members 29^a (see more particularly Figs. 1, 3, 4 and 11) and are adjustably mounted upon the bars 29 so that they may be positioned with reference to each other and to the medial line of the machine to accommodate the width of the blank 10 being operated upon.

Extending lengthwise of the machine and centrally thereof are two bars 60 and 61, said bars being sustained by standards 62 and 63, Fig. 5, at the infeed end of the machine and by similar standards 64 and 65, Figs. 4 and 6, at the discharge end of the machine, lateral stays as 66 being provided to brace the standards. The stays at the infeed end are secured to a block 67, Fig. 3, which in turn is embraced by and secured to the standards 62 and 63, and a second block 68 L-shaped in form is connected to standards 64 and 65 and to the stay at the discharge end of the machine. Journaled in the horizontal member of the block 68 is a shaft 69, said shaft at its outer end carrying a sprocket wheel 70, see more particularly Figs. 6 and 8, about which passes a sprocket chain 71, said chain in turn passing about idlers 72, 73, mounted on an arm 74 carried by a lever 75 normally drawn down by a spring 76, and about a sprocket 77 secured to one end of one of the shafts 18. Shafts 18 are periodically rotated, as will presently appear and as a consequence shaft 69 is likewise periodically rotated. Said shaft 69, see Fig. 8, has secured to its inner end a lifter cam 78 which underlies and cooperates with a rod 79 which is mounted for endwise reciprocation in a bearing block 80 and at its upper end bears upon the under face of a head 81 mounted to turn upon a cross pivot pin 82, which pin extends through vertically disposed elongated slots formed in the upper portion of the bearing block 80. The head block 81 swings about the pin 82 and is normally held in its vertical position by a spring 83, the head block having attached to its upper end a stop plate 84, (Figs. 1, 3, 6 and 8) which stands in the path of movement of the blank. The head block 81 is notched at its lower edge and is adapted to be held in its vertical position, when the rod 79 is upon the lower portion of the cam, by a fixed lug 84^a carried by the block 80 and adapted to enter the notches. When the parts are in the position shown in full lines in Fig. 8, the rod 79 is upon the lower portion of the cam 78 and consequently the spring will hold the rocking head 81 downwardly in locking engagement with the lug 84^a and so arrest the stop. When, however, the cam is rotated through approximately 260°, the rod 79 will be lifted and the upper end thereof bearing upon the under face

of the rocker head 81 will raise the same so as to free it from engagement with the locking lug 84, and when this disengagement is effected the blank which is constantly urged forward by the feed belts will throw the 70 rocker head 81 and the stop bar 84 to the left and out of the path of the stock.

As above noted, the shafts 18 are periodically rotated, and to effect such periodic rotation the shaft 41 is likewise periodically 75 driven. Said shaft 41 carried a large gear 85 which meshes with a pinion 86 mounted upon a shaft 87 (see Fig. 5) which derives its motion from a constantly rotating member 88 and an interposed clutch mechanism 80 having a constantly rotating element 89 and a shiftable clutch member embodying a sleeve 90. The shaft 41 has secured to it a cam 91 and an actuating arm 92 (see Figs. 5, 7, 8 and 9) the cam being adapted to operate upon a latch releasing mechanism while the actuating arm 92 operates upon the clutch shifting device. It is essential, of course, that the shafts 18 which carry the knives which notch the stock be in rotation 90 while the stock is arrested by the stop 84 and, consequently, the clutch must be in locking relation when the stock is at rest, and, on the other hand, the clutch must be thrown out and the shafts 18 at rest while 95 the stock is being fed forward. Fulcrumed between the bars 60 and 61 is a lever 93 provided with a cross plate 94 adapted when the lever is thrown in a vertical position to stand in the path of movement of the blank. The lever at its lower end carries a spring 100 pressed finger 95 which contacts with one end of a reciprocating bar 96, the opposite end of which bar bears against a lever 97 (Figs. 3 and 8) which lever is secured to a 105 shaft 98. Said shaft has secured to it a bail-shaped element 99 which is normally drawn upwardly by a spring 100, which action causes the lever 97 to always maintain contact with the reciprocating rod 96 110 and thus through such rod tend to maintain the lever 93 in its vertical position with the cross plate 94 in the path of movement of the blank. Said member 99 contacts the lower end of a latch lever 101 fulcrumed upon a 115 fixed portion of the machine, the lever being held against the bail 99 through the action of a spring 102. The upper end of said latch lever stands in line with an opening 103 formed in the lower portion of an arm 104 of a rocking lever, the opposite end of the lever being designated by 105. Said lever is fulcrumed upon a vertical pivot pin 106 and the arm 104 is normally thrown inward to the position shown in Fig. 9 by a 120 spring 107. Said spring surrounds a rod 108 which is secured to a fixed member 109 of the machine, the rod passing through an opening 125 formed in the lever. The arm 105, as will be seen upon ref. 130

erence to Figs. 7 and 8, extends downwardly and the lower end thereof is curved outwardly. Adjacent the upper end of the arm 105 the lever is provided with a roller 110 adapted to contact with the cam 91, heretofore referred to, said cam serving to rock the lever and to move the member 104 outwardly so that the latch lever 101 may pass in rear of the arm 104 through the action 10 of the spring 102 when the rod 96 is shifted to the left and the cross plate 94 comes to its vertical position (see Figs. 1 and 2). The clutch member 90 is released by the arm 92 which contacts a striker plate 111 secured 15 to the upper end of the swinging yoke 112. The clutch is thrown into operative relation by the lever arm 105, the lower outer curved end of which stands in line with the upper end of the yoke 112. Actuation is effected 20 through said lever 104, 105 by the spring 107 which throws the arm 104 inwardly and at the same time throws the lower end of arm 105 outwardly, swinging the yoke 112 into the position shown in Figs. 7 and 9. 25 When the parts are in the position shown in Fig. 2 the clutch is in its released position and the rod 96 is moved to the left (Fig. 8) at which time the cross plate 94 stands vertically in the path of the oncoming 30 blank. As the blank contacts the cross plate 94 it throws the lever 93 downwardly, moves rod 96 to the right, rocks the bail-shaped member 99 through lever 97 and the bail swings the lower end of lever 101 to the right withdrawing the upper end of the 35 lever from in rear of the lever arm 104 and permitting the spring 107 to throw the lever arm 104 inwardly and thereby bring the clutch into operative position. The blank 40 as it passes from the cross plate 94 comes against the stop 84 and is arrested. Immediately the clutch is thrown into locking 45 relation, the shafts 18 carrying the knives will be set in motion and cause the knives to pass downwardly through the stock and again move up to the position shown in Fig. 5, at which time the clutch will again be thrown out of operation through the contact 50 of the arm 92 with the plate 111. Prior to the contact of the arm 92 with the plate 111 cam 91 will have contacted the roll 110 and rocked the lever 105, 104, so as to throw the lever arm 105 out of the way of the yoke arm 112. At the same time the spring 55 107 will be put under compression. Immediately the stock has been cut the cam 78, which has been rotating, will lift the rod 79 and release the stop plate 84 permitting the blank to move forward. As the end of the 60 blank passes free of the cross plate 94 the spring 100 will rock the bail 99 and permit the latch lever 101 to pass behind the lever 104, locking it in its open position with the spring 107 under compression.

65 It will thus be seen that the various parts

are so timed that the blank is automatically arrested and when arrested the knife actuating mechanism will come into operation. When the knives have completed their operation the clutch is released and held in its 70 released position until the cut blank has moved forward and a new blank has taken its position, when the cycle of operations is again completed.

What is claimed is:—

1. In a machine for notching blanks, the combination of a pair of shafts arranged parallel to each other; a plurality of knives carried by each shaft; a series of fixed shearing blades located in the path of movement 80 of the knives carried by the shafts; and means for feeding a blank over the fixed blades.

2. In a machine for notching blanks, the combination of a pair of shafts arranged 85 parallel to each other; a plurality of knives carried by said shafts; a series of fixed shearing blades located in the path of movement of the knives carried by the shafts; a constantly acting means to feed the stock to 90 be cut over said fixed blades; means for arresting said stock when brought to proper position; and means for rotating the shafts when the stock is brought to rest.

3. In a machine for notching blanks, the combination of a pair of shafts arranged parallel to each other; a plurality of knives carried by said shafts, said knives being arranged in stepped relation about said shafts; a series of fixed shearing blades located in 100 the path of movement of the knives carried by the shafts; constantly acting means to feed the stock to be cut over said fixed blades; means for arresting said stock when brought to proper position; and means for rotating the shafts when the stock is brought 105 to rest.

4. In a machine for notching blanks, the combination of a pair of shafts arranged parallel to each other; a plurality of knives carried by said shafts; a series of flexed shearing blades located in the path of movement of the knives carried by the shafts; constantly acting means to feed the stock to 110 be cut over said fixed blades; means for arresting said stock when brought to proper position; means for rotating the shafts when the stock is brought to rest; and means actuated by the stock for causing said last named means to function.

5. In a machine for notching blanks, the combination of a pair of shafts arranged parallel to each other; a plurality of knives carried by said shafts; a series of fixed shearing blades located in the path of movement of the knives carried by the shaft; constantly acting means to feed the stock to be 115 cut over said fixed blades; means for arresting said stock when brought to proper position; and means for rotating the shafts when 120 125 130

- the stock is brought to rest; and means normally standing in the path of movement of the stock and actuated by the movement thereof for causing said last named means 5 to function.
6. In a machine for notching blanks, the combination of a pair of supporting beams arranged parallel to each other; a pair of similarly arranged shafts; a series of arms 10 extending from each shaft to the adjacent beam; a shearing blade supported upon each arm; a series of blades carried by each shaft and adapted to cooperate with the shearing blades; and means for advancing the stock 15 to be cut over the shearing blades.
7. In a machine for notching blanks, the combination of a pair of supporting frames; a second pair of such frames arranged opposite thereto; means for adjusting said 20 frames laterally toward and from each other; a beam carried by each pair of said frames; a shaft carried by each pair of frames; a series of arms supported by each shaft and the adjacent beam, said arms being adjustable toward and from each other; a shearing blade carried by each arm; and a plurality of knives carried by said shafts 25 and adapted as the shafts are rotated to cooperate with the shearing blades to notch 30 the blank.
8. In a machine for notching blanks, the combination of constantly moving feed mechanism for the blank; notching mechanism; means for arresting the blank in 35 proper position with reference to said cutting mechanism while the feed mechanism still continues in movement; actuating mechanism for the cutting mechanism, embodying a clutch; and means controlled by 40 the stock for effecting actuation of the clutch as the blank comes to rest.
9. In a machine for notching blanks, the combination of constantly operating feed
- mechanism for the blank; notching mechanism; means for arresting the blank in 45 proper position with reference to said cutting mechanism; actuating mechanism for the cutting mechanism, embodying a clutch; and means controlled by the stock for effecting actuation of the clutch as the blank 50 comes to rest.
10. In a machine for notching blanks, the combination of two pairs of oppositely disposed belts between and by which the blanks are fed; means for constantly moving said 55 belts; cutting mechanism located to each side of the belts; a stop device for arresting the blank when the same is in proper position with reference to said cutting mechanism; means operated by the blank to bring the 60 cutting mechanism into operation; and means operating in timed relation to the cutting mechanism to release the notched blank.
11. In a machine for notching blanks, the 65 combination of a plurality of fixed shearing blades; means for positioning the stock to be cut over said blades; a shaft; means for rotating the same; and a plurality of knives carried by the shaft and adapted to 70 cooperate with the fixed blades, said knives being arranged in spaced or offset relation about the axis of the shaft.
12. In a machine for notching blanks, the 75 combination of two series of oppositely arranged fixed shearing blades; a shaft arranged adjacent to each series; means for rotating said shafts; and a series of knives carried by each shaft adapted to cooperate with the fixed blades, the knives on each 80 shaft being arranged in spaced or offset relation about the axis of the shaft.

In testimony whereof I have signed my name to this specification.

JOHN A. MOORE.
